Primary Examiner — Patricia A Palasik(74) *Attorney, Agent, or Firm* — Eugenio J. Torres-Oyola;
Victor M. Rodriguez-Reyes; Rafael Rodriguez-Muriel**CLAIM**The ornamental design for a tillage implement, as shown and
described.**DESCRIPTION**FIG. 1 is a first perspective view of a tillage implement,
showing the present design.

FIG. 2 is a second perspective view thereof.

FIG. 3 is a first plan view thereof.

FIG. 4 is a second plan view thereof.

FIG. 5 is a side elevation view thereof; and,

FIG. 6 is a cross-sectional view taken along line **6-6** thereof.
The broken line shown across the surface of the claim in
FIG. 1 indicates the viewing plane for the cross-sectional
view shown in FIG. 6 and forms no part of the claimed
design.**1 Claim, 6 Drawing Sheets**FIG. 1

FIG. 2

FIG. 3

FIG. 4

FIG. 5

FIG. 6
